GEORGE ERDMAN, OF HUDSON, NEW YORK, ASSIGNOR TO GIFFORD-WOOD COMPANY, OF HUDSON, NEW YORK, A CORPORATION OF NEW YORK

CONVEYER FLIGHT

Application filed June 21, 1928. Serial No. 287,129.

This invention relates to conveyer flights and, among other objects, aims to provide an improved flight adapted to collapse when subjected to side strains.

5 In the drawing:

Fig. 1 is an elevation of a conveyer provided with a flight embodying the invention;

Fig. 2 is an end view of the same;

10 Fig. 3 is a side elevation of the improved flight and drawn on a larger scale;

Fig. 4 is a sectional view taken on the line 4—4 of Fig. 3; and

Fig. 5 is a sectional view taken on the line 5—5 of Fig. 3.

15 The herein described flight is particularly adapted to be used in ice manufacturing plants, for example, where cakes of ice are delivered from a slat conveyer moving in one direction to an overhead conveyer moving at an angle thereto.

20 Referring particularly to the drawings, there is shown a slat conveyer 10 adapted to deliver cakes of ice 11 to a point directly beneath an overhead conveyer 12 which is 25 mounted on the usual sprockets and, in the present instance, travels at right angles to the conveyer 10. Suitable automatic switches (not shown) are provided to prevent the cakes from passing beyond the longitudinal axis of the overhead conveyer.

25 Herein, the conveyer chain 12 is shown as being slidably supported between the sprockets on the flanges of angle irons 13 and 14 which form guides for the chain and prevent it from sagging.

30 When the ice cake is beneath the conveyer 12, it is adapted to be pushed along on a skid or trackway beneath said conveyer by a depending flight which is fast upon conveyer chain 12 and extends 35 downwardly between the flanges of the lower guides 14 to a point below the top of the ice cake.

35 It sometimes happens that the two conveyers are out of synchronism, that is, one of the flights of the overhead conveyer may be in the path of the ice cake as it is being moved into position beneath said conveyer by the slat conveyer 10. At such a time, the cake would strike the side of the flight, 40 which would probably damage the flight and

chip the ice. If the flight survived the blow, the cake would be tipped over and would have to be righted before operation could proceed. The present invention overcomes these defects by providing improved flights 15 on the overhead conveyer which are adapted to swing out of the way upon being struck a side blow by the ice cake, and to move back automatically to normal position again.

45 Herein, each of the flights 15 is shown as comprising a substantially inverted U shaped block 16 forming one of the links of the chain 12. See Fig. 3. These flights may be spaced any distance apart as conditions require. The lower ends of the side arms 17 are provided with aligned longitudinal apertures 18 forming bearings for a shaft 19 which extends therethrough and is held in place by cotter pins 20 or the like. 50 Rockably mounted on the shaft 19 is a pusher member or plate 21, the lower end of which extends below the top of the ice cake so that its front face 22 will engage the cake, while the upper end of the rear face bears 55 against the inner face of one of the arms 17. The lower end of the plate is somewhat wider than the upper end so as to present a substantial bearing surface to engage the ice cake without danger of chipping it.

60 In order to retain the plate 21 in the position shown relative to the block 16, the upper rear face of the plate is provided with a V shaped projection 23 which is held seated in a corresponding notch 24 in the inner face of the adjacent arm 17 by an expansile coiled spring 25 mounted on the shaft 19 between the front face of the plate and the other arm 17, the plate being of less width than the distance between the arms. When the plate 26 65 is rocked, the projection 23 will ride partly up the inclined face of the notch 24 and the spring 25 will be compressed. When pressure on the side of the plate is released, the projection will be forced back into its seat in the notch by the spring. It will be apparent that if the side of the plate is in the path of an ice cake on the conveyer 10, it will be 70 rocked on the shaft when struck and thus permit the cake to pass beneath its lower

100

edge. The plate will then slide along on top of the cake until it reaches the end of the cake where it will be returned to its normal position, while the cake will be pushed by the next flight.

To prevent excessive wear to the parts due to too much swinging of the plate when returned to normal position, the upper end of the plate is provided with a central up-standing longitudinal lug 26 which engages a shoulder 27, extending downwardly from the block 16 between the side arms 17. This shoulder is, of course, on the side opposite to the approaching ice cake, so as not to interfere with the swinging of the plate when struck, and at the same time to form a positive stop for the plate when it is returned to normal position.

By forming a notch in the inner face of each arm, the block and plate may be reversed relative to each other so that the flight may be used on a conveyer moving in either direction or when the ice is approaching the conveyer from either side. A suitable recess 28 may be provided in the bottom of each of the notches 24 to form a seat for the end of the spring, if desired.

From the foregoing description it will be apparent that an improved conveyer flight has been provided which will collapse following a side blow, so as to prevent any damage to the flight or to the object by which it is struck. Further, it is simple in construction and inexpensive to manufacture and being made reversible, can be used in various installations.

Obviously, the present invention is not restricted to the particular embodiment thereof herein shown and described.

What is claimed is:—

1. In combination with a conveyer chain, a link; a depending bearing portion at each end of the link; a shaft arranged longitudinally of the link and in the bearings; a pusher plate rockably mounted on the shaft and extending below the bearings; a V-shaped projection on the rear face of the plate; one inner face of the bearings having a corresponding V-shaped notch to form a seat for the projection; and a coiled spring on the shaft between the front of the plate and the adjacent bearing to hold the V-shaped projection normally in its notch.

2. A conveyer chain link comprising a U-shaped block; a longitudinal shaft carried by the block; a pusher plate pivotally mounted on the block; means to retain the plate in fixed relation to the block but to permit the plate to swing on the shaft when struck on the side; a lug on the top of the plate; and a shoulder on the block to form a positive stop for the plate when in normal position.

3. In combination with a conveyer chain, a link; a bearing at each end of the link; a shaft arranged longitudinally of the link and

in the bearings; a pusher plate rockably mounted on the shaft and extending below the bearings; a V-shaped projection on the rear end of the plate; each of the inner faces of the bearings having a V-shaped notch to form seats for the projection and permit the plate to be reversed relative to the block; an expansible coiled spring on the shaft between the front of the plate and the adjacent bearing; a lug on top of the plate; and a shoulder on one side of the block engageable by the lug to limit the rocking of the plate in one direction.

In testimony, that I claim the foregoing as my own, I have hereto affixed my signature.

GEORGE ERDMAN.
